UNITED STATES PATENT OFFICE.

FREDRICK ROTHMUNT, OF SAN FRANCISCO, CALIFORNIA.

PLOW.

SPECIFICATION forming part of Letters Patent No. 349,750, dated September 28, 1886.

Application filed February 23, 1886. Serial No. 192,930. (No model.)

To all whom it may concern:

Be it known that I, FREDRICK ROTHMUNT, a citizen of the United States, residing at San Francisco, in the county of San Francisco and 5 State of California, have invented a new and useful Improvement in Plows, of which the following is a specification.

It is a well-known fact that in the use of plows the parts known as the "share," the 10 "neck" or "shield," and the "landsides" are the first portions to wear away, requiring the substitution of new parts before the plow is laid aside as useless; hence the object of my 15 invention is to so construct these parts as to render them capable of being used a longer time than heretofore.

My invention also relates to a means for attaching the mold-board to the plow and strengthening its connection with the landside. I accomplish these objects by the means 20 illustrated in the accompanying drawings, in which—

Figure 1 is a side view of my improved plow with mold-board removed. Fig. 2 is a plan 25 of the same. Fig. 3 is a section taken through the line $x-x$, Fig. 2. Fig. 4 is a section taken through the line $x-y$, Fig. 2, showing the connection of mold-board to the landside.

Referring to the accompanying drawings, 30 forming a part of this specification, A represents the neck or shield of my plow, which is made rounding outwardly, as at A^x , in vertical section, Fig. 3. By this means the wear so incident upon that point is compensated 35 for and the neck or shield will last a much longer period of time. The point of the plow is made thicker from its extreme outer point to its juncture with the outer portion of the neck or shield, as at B, Fig. 1, and gradually 40 tapers to the end of the share, thus also compensating for the wear upon this part of the plow-point. The rear end of the neck or shield is provided with an extension-piece 45 with lugs C, forming a square shoulder for the mold-board, and a means for bolting it to the neck piece or shield, as shown at D.

In order to compensate for the wearing away of the outer end of the landside, this portion thereof is made thicker, as at E, and the landside is composed of two parts joined together 50 by a lap-joint, as at F, so that when the rear or outer portion is worn away a new piece may be substituted for it, while the board or edge of the shoe G is tapering outward or backward from the jointed connection with its 55 counterpart.

In order to strengthen and support the divided landside, a curved strap, H, is bolted to it, and extends over toward the mold-board, at which point the upper end of a bent strap, I, 60 is connected to it by bolts, while the lower end is connected to a rod, J, bolted to the lower edge of the mold-board. The rod J is provided with a nut for adjustment of the parts. Thus it will be seen that the parts of 65 a plow that are most liable to excessive wear are fortified and means provided for supplying new parts for those that are worn out.

Having thus described my invention, what I claim, and desire to secure by Letters Patent, 70 is—

The combination of the neck or shield A, made rounding outwardly at A^x , and provided rearwardly with an extension having lugs C, which form a shoulder, the mold-board secured by means of said shoulder, the plow-point thickened from its outer extreme to its junction with the neck at B, the divided landside having a lap-joint, and means for attaching and adjusting the same to the mold-board, 75 consisting of the bent strap H, bolted to the inner face of the rear portion of the landside, and connecting with the mold-board by means of the curved intermediate strap, I, and rod J, 80 substantially as set forth and shown.

In testimony that I claim the foregoing I have hereunto set my hand and seal., 85

FREDRICK ROTHMUNT. [L. S.]
